UNITED STATES PATENT OFFICE.

CHARLES D. McDONALD, OF FULLERTON, CALIFORNIA.

BED.

Application filed November 2, 1925. Serial No. 66,280.

This invention relates to collapsible and camp beds.

It is an object of the invention to provide a bed which can be collapsed into a very small and compact form and which is of very light, but substantial, structure and which can be quickly and very easily extended and set up for use.

An object is to provide a mattress support which can be rolled into small form and is interlockable with and separable from its complementary bed frame.

An object is to provide a bed having foldable end sections and foldable legs, and to provide for bracing of the said sections in different positions.

Other objects and advantages will be made manifest in the following specification of an embodiment of the invention; it being understood that modifications, variations and adaptations may be resorted to within the spirit and scope of the invention as it is here claimed.

Figure 1 is a side elevation of the bed adjusted as a hammock. Figure 2 is a perspective of the bed; the mattress support being broken away. Figure 3 is an end view of the collapsed frame. Figure 4 is an end view of the extended frame. Figure 5 is a perspective of the rail end and its saddle. Figure 6 is an end view of a saddle. Figure 7 is a perspective of a hinge leaf of the saddle. Figure 8 is a plan of the blank of a saddle.

The bed includes a pair of side rails 2 having at the lower corner ends hinges 3 to which are attached legs 4 which swing down from the rail to an outwardly inclined position. Stout, folding braces 5 connect the legs to the rail for bracing the legs in the extended position.

When extended the upper end of each leg forms a shoulder beyond the rail end and on this shoulder may rest a foldable stub rail 2^a which is connected to its near rail by a hinge having its pin 6 in the top plane of the rail so that the stub 2^a can be folded over on top of the rail in collapsed form. A hook-brace 7 is pivoted in each leg 4 and its hooked end 8 is insertable in holes 9 and 10 in the stub rail 2^a.

A pair of rail structures just described are foldably connected in parallel relation by a collapsible means of the "lazy tongs" type. This means includes a set of link members

11-11^a connected at 12 to struts 13 and pivoted at 14 on the upper ends of opposite legs 4. Levers 17-18 are connected at 19 and are pivoted at 20-21 near the bottom ends of the legs. The struts are connected together at 22.

Therefore, as the side rails are pulled away from each other, as in Fig. 3, the levers 17-18 open out into alignment and automatically move the struts 13 up between the legs 4. This swings the brace links 11-11^a to brace the struts and the legs. When the rails have been spread an end stile 25 is mounted on the extended ends of one pair of stubs 2^a and the mattress support 26 is unrolled toward the opposite end of the bed and the other end stile is connected to the relative stubs before these are fully extended. The stubs are then pulled outward and pressed down to the plane of the rails. This places springs 28 under high tension and they hold the stubs down on the tops of the legs 4.

The stiles 25 combine with the bottom levers 17-18 to lock the frame in fully spread position.

To permit the legs to fold up close, the lazy tong linkage on one end of the bed is connected or mounted on the outer faces of their legs while the linkage of the legs at the opposite end of the bed is on the under face of the legs.

The support 26 can be pulled tight by pressing down the end stubs 2^a below the center of hinges 6; the springs 28 highly tensioning the fabric and pulling the stubs 2^a down against the tops of the legs 4.

A hammock may be formed by tipping up the stubs 2^a as in Fig. 1, and placing the brace hooks in holes 10. The edges of the support 26 are wholly free from the rails and may, therefore, freely sag down between the rails and form a very comfortable hammock.

When the end bars 25 are removed the whole frame can be collapsed into a small bundle form, and the support 26 can be rolled into a small roll.

To obtain a very strong structure and good connections for the legs and the stub ends 2^a, I provide a saddle forming a central seat portion 30 having upturned side lugs 31 here shown as of triangular form. The top corners of the lugs 31 form bearings 32 for the hinge pins 6. At the outer, lower corners of the seat 30 is a pair of bearing ears 3^a for

the pin 3^b of its hinge leaf 3. The pins 3^b and 6 are disposed about in the end plane of the rail 2.

The leaves 3^a and 6^a of the hinges are substantially duplicate.

A stout rivet 33 secures the saddle in place on the end of its rails, and a hole 34 in the seat 30 provides for a fastening screw if desired.

What is claimed is:

1. A bed having side rails and end pairs of legs foldable on the rails, levers pivoted at their ends on respective pairs of legs and connected together at their inner ends and alining when extended, struts whose inner ends are connected and whose outer ends are pivoted on the levers near the pivots thereof, and diagonal brace links connected to the legs and connected to the struts at points between their ends.

2. A bed having side rails and end pairs of legs foldable on the rails, levers pivoted at their ends on respective pairs of legs and connected together at their inner ends and alining when extended, struts whose inner ends are connected and whose outer ends are pivoted on the levers near the pivots thereof,

and diagonal brace links connected to the legs and connected to the struts at points between their ends, and near their attachment to the levers.

3. An adjustable bed structure including side rails having on their ends saddles with bottom seat portions and upturned side hinge pintle plates which are fixedly secured to the rails; the upper corners of the plates providing bearing lugs for hinge pins, bearing ears at the outer corners of the seat portions for hinge pins, and hinge leaves pivoted on said lugs and ears and carrying rail stubs 40 movable into alinement with the rails, and bed legs.

4. An adjustable bed structure including side rails each having saddle hangers on its ends, said hangers having side plates clamped on the ends of the rail and having an upper pair and a lower pair of bearings for hinge pins, an upper hinge leaf and a lower hinge leaf in respective bearings at the end corners of the plates of each saddle, an extension rail part carried by one leaf, and a leg carried by the lower leaf.

CHAS. D. McDONALD.
